(57) **CLAIM**

The ornamental design for a grill, as shown and described.

DESCRIPTION

FIG. 1 is a front perspective view of a grill.

FIG. 2 is a front view of the grill.

FIG. 3 is a right side view of the grill.

FIG. 4 is a left side view of the grill.

FIG. 5 is a top view of the grill.

FIG. 6 is a front perspective view of an alternate grill with a wood finish.

FIG. 7 is a front view of the grill of FIG. 6.

FIG. 8 is a right side view of the grill of FIG. 6.

FIG. 9 is a left side view of the grill of FIG. 6.

FIG. 10 is a top view of the grill of FIG. 6.

FIG. 11 is a front perspective view of a further alternate grill with a stone finish.

FIG. 12 is a front view of the grill of FIG. 11.

FIG. 13 is a right side view of the grill of FIG. 11.

FIG. 14 is a left side view of the grill of FIG. 11; and,

FIG. 15 is a top view of the grill of FIG. 11.

The broken lines in the drawings illustrate portions of the article that form no part of the claimed design. The back view and bottom view of the grill form no part of the claimed design.

1 Claim, 15 Drawing Sheets
